UNITED STATES PATENT OFFICE.

ISAAC J. BAXTER, OF PEEKSKILL, NEW YORK.

DESIGN FOR A SINK-LEG.

SPECIFICATION forming part of Design No. 16,650, dated April 20, 1886.

Application filed March 11, 1886. Serial No. 194,893. Term of patent 31 years.

To all whom it may concern:

Be it known that I, ISAAC JAY BAXTER, a citizen of the United States, residing at Peekskill, in the county of Westchester and State of New York, have invented and produced a new and original Design for a Sink-Leg, of which the following is a specification, reference being had to the accompanying drawings, forming part thereof.

10 Figure 1 is an elevation of my design of a leg for sinks, and Fig. 2 is a cross-sectional view through line *d*. Fig. 3 is a cross-sectional view through line *e*, and Fig. 4 is a cross-sectional view through line *f*.

15 The dotted lines in Fig. 1 indicate the sink, to which the leg is attached in the ordinary manner.

The cross-sectional views are made of exaggerated sizes for the purpose of clearness.

20 My design consists of a fluted head, *a*, which spreads at its base to a broader nearly square surface, *d*, to which I affix an ornament, as shown. The edges of this surface *d* are carried back in the form shown by Fig. 2. From 25 the base of the surface *d* the sides or edges curve sharply toward each other to the dis-

tance of about half an inch on each side, as shown, and thence the leg has a gradual and uniform taper to its lower end. About three inches of the bottom of the leg is given an 30 ogee curve forward, forming the foot *f* of the leg, on which I place an ornament, as shown. The form of the sides or edges of this portion of the leg is clearly shown by Fig. 4. Between the ornamental foot *f* and the broad surface *d* there is no ornamentation except that afforded by the flat marginal configuration, rounded and beveled corners, and the rising angular front, as shown in perspective by Fig. 1 and in cross-section by Fig. 4. 35

I claim—

The design for a sink-leg, comprising the fluted head *a*, ornamental surface *d*, the gradual taper from *d* to the base having a flat marginal configuration, beveled corners, and rising angular front, and the curved ornamental foot *f*, as herein shown and described. 45

I. J. BAXTER.
